United States Patent Office

Des. 216,660
Patented Mar. 3, 1970

216,660

HAMBURGER BUN

Theodore A. Corn, 1000 North Point, San Francisco,
Calif. 94109, and Robert M. Harlick, 2330 Wexford,
South San Francisco, Calif. 94080

Filed Apr. 10, 1969, Ser. No. 16,676

Term of patent 14 years

Int. Cl. D1—01

U.S. Cl. D1—24

FIG_1

FIG. 1 is a top view of a hamburger bun, showing our new design;

FIG. 2 is a bottom view of the bun shown in FIG. 1;

FIG. 3 is a side elevational view of the bun shown in FIG. 1; and

FIG. 4 is a perspective view of the bun shown in FIG. 1.

We claim:

The ornamental design for a hamburger bun, as shown.
